11 Claims. (Cl. 33—31)

This invention relates generally to ellipsographs, or implements to scribe or draw ellipses.

Many ellipsographs have been proposed, but none have achieved broad acceptance, because most of the devices suggested for the purpose are either cumbersome and expensive or are inaccurate, slow, hard to operate or of limited usefulness.

It is an object of this invention to provide an inexpensive ellipsograph capable of rapidly tracing ellipses of any desired proportion and size between a point and the maximum size circle for which the instrument is designed.

It is a further object to provide an ellipsograph operating with a maximum of ease and mathematical precision.

Another object is to provide means capable of cooperation with existing drafting machines, so as to temporarily convert them into large scale ellipsographs, without impairing their normal function.

The construction necessary to accomplish these objectives will be explained by reference to the appended drawings, in which:

Fig. I is a plan view of an ellipsograph incorporating the invention.

Fig. II is a bottom elevation partially in section along the line II—II of Fig. I.

Fig. III is a section along the line III—III of Fig. I.

Fig. IV is a section also along the line III—III of Fig. I, but showing an ink pen installed instead of a lead pencil.

Fig. V shows the adaptation of the invention to a conventional drafting machine.

Fig. VI is a section along the line VI—VI marked in drawing V.

Fig. VII is a reduced scale drawing of a drafting board, upon which a drafting machine with the ellipsograph attachment of Fig. V are installed.

Fig. VIII represents a graphical construction for an ellipse, which will be used to illustrate the theory of the invention.

Fig. IX is the plan view of an alternative construction.

Fig. X is an enlarged section along the line X—X of Fig. IX.

Referring to the drawings in which similar reference characters designate similar parts throughout, the ellipsograph of Fig. I comprises a rectangular base plate 1, upon which the elements of the ellipsograph are mounted. Preferably it is made out of cellulose acetate or a similar transparent plastic. It is locally reinforced by the blocks 2 and 3 fastened to it by means of rivets, screws or glue, for the purpose of mounting the clevis pins 4, 5 and 6 which are pressed into the reinforcements. On the pivot pin 4 a hollow spindle 7 can revolve freely. On it are mounted a circular disc 8, a spacing washer 9, another circular disc 10 and an indexing washer 11. The outer end of the spindle 7 has a threaded portion 12, which screws into the knob 13. When this knob is tightened, the spindle 7 and all the parts 8, 9, 10, 11 and 13

become a unit assembly, referred to as the disc assembly, which may be installed onto pin 4 and rotated with respect thereto.

The discs 8 and 10 are preferably also made out of plastic. They have been provided with a slot 14, which engages the flat side 15 milled on the spindle. In Fig. I the left hand side of the knob has been omitted to show this flat 15, it being understood that the right hand side of the spindle is fashioned in the same manner. This view shows that also the washer 11 engages the flat so that neither the discs, nor the washer can revolve with respect to the spindle, even if the knob were not tightened completely.

The discs 8 and 10 are shown eccentrically mounted with respect to the centerline of the pivot pin 4. The amount of eccentricity can be read off at the mark 16 on the washer 11, which is beveled to facilitate reading at the graduated scale indicated at 17. When the zero on the graduations is lined up with the mark 16 on the washer 11, the disc will be exactly concentric with the pin 4. In the drawing disc 10 is shown installed with more eccentricity than disc 8, but it must be understood that either disc may be adjusted with any desired eccentricity. If the ellipse to be drawn is to have its major axis in a vertical direction, disc 8 would be adjusted with the larger amount of eccentricity.

A second unit assembly is shown generally at 21. It has the form of a square and consists of 2 pairs of strips of plastic 22a, 22b, 23a and 23b, separated by spacers 19 at the corners in such a manner that the opposite sides are in the same plane. The strips and spacers are glued, riveted or fastened together by means of screws in such a manner that the strips 22a and 22b are parallel, perpendicular to the strip 23a, and a distance apart equal to the diameter of the disc 8, while the strips 23a and 23b are parallel and a distance apart equal to the diameter of the disc 10. To facilitate mounting the disc assembly on pin 4 and inside the square, the lower disc 8 is preferably made slightly smaller than the upper disc 10. Further the thickness of the spacer 19 is equal to that of the washer 9 and that of the strips equal to that of the discs, so that it will be possible to adjust the length of the pins or feet 24 in such a manner that the upper and lower surfaces of the strips correspond to the upper and lower surfaces of the discs. In this manner the disc 8 will be in contact with the edges 18a and 18b of the strips 22a and 22b, while the disc 10 contacts the edges 20a and 20b of the strips 23a and 23b.

The movement of the square is constrained to permit translation in any direction with the pins 24 sliding over the base plate or drawing paper underneath it, as the case may be, but rotation is prevented. Thus, no matter how the square moves, the edges 18 and 20 will remain parallel to their original position and in contact with the discs 8 and 10. This constraint is obtained as follows:

Two identical links 25 and 26 are arranged to pivot around the pins 5 and 6 and secured thereto by means of suitable washers 40 and grip- or snap rings 41. At their other extremity they may pivot around the pins 29 and 30, which are pressed into the floating plate or knee piece 31. The distance 29—30 is equal to the distance between the pins 5 and 6. Thus the pins 5, 6, 29 and 30 are always at the cornerpoints of a parallelogram and since the side 5—6 thereof is fixed, the side 29—30 is free to swing, but it must always remain parallel to the side 5—6. Thus the knee 31 cannot rotate. The plane in which it moves is further determined by the length of the pin 42 in such a manner that its upper surface coincides with the plane of the upper surface of strip 23 and of the disc 10. Spacers 27 and 28 are used to maintain the links 25 and 26 in a plane parallel thereto.

At all ends the same washer and gripping combination secures the links.

In the knee piece 31 two additional pins 32 and 33 are pressed, in such a manner that the direction 32-33 is perpendicular to that of 29-30. The links 34 and 35 can pivot around these pins 32 and 33, while their other extremities may pivot around the pins 36 and 37, which are pressed into the corners of the square parallel to all other pivot pins. The distance between 36 and 37 is equal to the distance between 32 and 33. Thus the pins 32, 33, 36 and 37 are again at the corner-points of a parallelogram having one side 32-33, constrained to remain perpendicular to 29-30, hence to 5-6. Evidently the square is free to move in all directions, but it cannot rotate.

To operate the device the discs 8 and 10 are first adjusted so that their eccentricities are respectively equal to the vertical and horizontal half axes of the desired ellipse. After tightening the knob, the disc assembly is entered inside the square and mounted on the pin 4. After this the knob is given one or more rotations in either direction. As is demonstrated below each point of the square will describe the desired ellipse during this rotation, therefore any point on it may be used to mount a scribe. In Fig. I the upper left corner of the square is used for this purpose.

Fig. III shows a section through a scribe adapted to the use of pencil lead. A bushing 38 is pressed into a suitable opening bored in the square assembly. The pencil guide 39, made to have a sliding fit in the bushing bore, is inserted therein and locked by means of the screw 43. This pencil guide has a central hole into which a standard lead 44 can be inserted with a sliding fit. The weight 45 can be slipped over the outside of the pencil guide. In it is a split collet 46, which after tightening of the nut 47, grips the lead 44 and locks it tight. Thus the weight, collet, nut and lead form a tight assembly that may be readily inserted or withdrawn from the pencil guide. The weight 45 is proportioned so as to exert sufficient pressure on the point 48 of the lead to provide a satisfactory black line on the paper.

Fig. IV shows how a standard inkwell type of a pen 48a may be inserted in the bushing 38 and locked with the screw 43. Obviously any other scribe may be used, such as a brass rod for scribing on steel instead of paper and the device could even be proportioned so as to guide a cutting tool or torch in an elliptical path.

The position of the square, hence of the scribe, in Fig. I corresponds to the upper end of the vertical axis of the ellipse, because the disc 8 is in its top dead center. Therefore a vertical line drawn through the center of the scribe is this vertical axis and the side 49 of the base 1 runs parallel thereto at a fixed distance A. The horizontal axis of the ellipse to be traced is a horizontal line drawn at a distance below the scribe point equal to the eccentricity of disc 8. This axis is at a distance B from the side 50 of base 1. The distances A and B are invariable, which may be verified by adjusting both discs 8 and 10 to zero eccentricity. This puts the scribe exactly at the intersection of the two axes of the ellipse.

In Fig. I the distances A and B are both equal to two units of length of the scale shown on disc 10. Thus after the draftsman has determined the axes of the ellipse to be drawn, he draws parallel thereto two perpendicular lines, 2 units of length to the right and below these axes and lines up the edges 49 and 50 of the base 1 with these lines, which puts the instrument in the exact location needed to locate the ellipse correctly. He now fixes the base 1 by means of tape, thumbtacks or other means in this position, adjusts the disc assembly and traces the curve.

It is to be noted that the strips 22a and 23a could be omitted if a spring were used to urge the edges 18b and 20b in contact with the discs 8 and 10. In that case

the scribe would have to be mounted on an extension of either the strip 22b or 23b. Such a design was actually constructed and tested, but it was found difficult to operate and to produce inaccurate results because of the variable torque, friction and deflections in the mechanism, all caused by a spring less than two ounces of tension.

It is further to be noted that the knee piece 31 has only one degree of freedom, this is: only one dimension is necessary to completely determine its position. Such a dimension could be the angle of rotation of the link 26 with respect to a vertical line through the center of pin 6, or it might be the distance of the center of pin 30 to the side 49 of the base, or any other such dimension. Furthermore each point of the knee travels on an arc with a radius equal to the length of the links 25 or 26.

It is further to be noted that the square 21 has two degrees of freedom so that two dimensions must be given to determine its position. These might be the coordinates of the center of the square, or any other point thereof, with respect to any system of axes, or any other arbitrary pair of dimensions. Thus the square has freedom of translatory movement in a plane, but not of rotation.

Conversely any other means controlling the movement of a square, as described, to permit its translation in a plane without permitting its rotation, will be suitable for the construction of an ellipsograph conforming this invention. As an example the well known drafting machine shown in Fig. VII constrains two perpendicular scales for this type of motion. Therefore if a square substantially as described were attached to the scales 51 and 52 or the scale bracket 53, only a disc assembly and its pivot pin 4 are needed to construct an ellipsograph of the type described, provided the discs are made to fit the square and register with the proper edges 18 and 20 thereof. As has already been mentioned above the discs do not have to be equal in diameter, therefore a rectangle could be used, although this would limit the vertical and horizontal axes unequally.

Fig. V shows how a square, constructed as described above, may be bolted to the scales 51 and 52 by means of screws 54. In general a spacing washer 55 will be needed to adjust the square so that its inner edges 18 and 20 may properly contact the periphery of the discs 8 and 10. The drawing shows in the upper right hand corner of the square the bushing 38 suitable for the installation of the pencilguide or inkpen shown in Figs. III and IV. The base plate carries only the pin 4 and there is no essential difference in any of the parts of the disc assembly previously described in connection with Fig. I.

Since the scales 51 and 52 are provided with excellent graduations, the adjustment of the disc assembly may be simplified. For this purpose a pin 56, of the same proportions as the pin 4, is installed on top of the strip 23a. The disc assembly is mounted thereon with both discs approximately in the concentric position. Next the disc, which is to have the smallest eccentricity, is moved to the right until the scale reading at its periphery corresponds to the desired eccentricity. This operation is repeated with the other disc after which the knob is tightened. Next the base plate 1 is installed in the proper location by lining up its edges 49 and 50 with the lines already drawn on the paper at constant distances from the center of the ellipse and after securing the base plate to the drawing, the disc assembly is introduced into the square and mounted on the pin 4. When the scribe is in position, one turn of the knob 13 will produce the desired ellipse.

The ellipsograph shown in Figs. IX and X differs from the one of Fig. I only in some construction details and in the method of adjusting the eccentricity of the discs 8 and 10 with respect to the spindle 7.

The square 21 is made out of a single flat sheet of metal, having an internal square opening, the sides of which have been formed by bending part of the metal to make an angle of 90° with the plane of the sheet. Fig. X shows how the lips 20a and 20b have further been provided with flanges 57, so that the periphery of disc 10 may contact the inner surfaces of the lips and the disc be prevented from moving in the direction of knob 13 by the flanges. In the same way lips 18a and 18b are formed by bending part of the metal in the opposite direction to provide lips having surfaces and flanges 58 to encase disc 8.

After the discs have been assembled to the square 21, the washer 9 is installed, to separate them from each other. The flats 15, milled on the spindle 7 in the constructions of Fig. I and Fig. V, have been machined on this washer and consequently the discs must be sprung slightly to permit the assembly of the washer 9. Once this washer is installed, the discs can no longer be independently moved to any arbitrary position within the square, the centers of the discs 8 and 10 and of the washer being compelled to remain in the same plane because of the flats on the washer.

The spindle 7 may now be inserted through the hole in the washer, after which the knob assembly is mounted and held in place by means of the special nut 59, engaging the threaded portion 12 on the spindle 7.

The knob assembly consists of a lower shell 60, carrying two screws 61 and a cover 62. Nuts 63 hold the two shells together against the action of the springs 64 and 65. The upper spring 64 acts via the washer 66 on the sleeve 67 and reacts directly on the cover 62. The shoulder 68 on this sleeve is in contact with the lower shell 60 before the knob is installed. The lower spring 65 acts directly on the lower shell 60 and reacts on the cover 62 via the bushing 69.

After installing the knob assembly on the spindle 7 and securing it by means of the nut 59, the lower end of the sleeve 67 will be in contact with the washer 9 and the shoulder 68 will be free from the lower shell 60, so that the upper spring is compressed a little more. The load of this spring therefore serves only to clamp the lower disc 8 between the washer 9 and the flange 70 of the spindle 7.

If the nuts 63 are now loosened up, the lower spring 65 transfers its load via the shell 60 to the disc 10. This load is transferred through the disc 10 to the washer 9, to the disc 8 and through disc 8 to the flange 70. Therefore disc 10 is subject to an axial clamping force equal to the load of the lower spring 65 and disc 8 to a force equal to the load of both springs. Since both springs react on the cover 62, the latter reacts on the nut 59 with the same force as is applied to flange 70 and the spindle is loaded in tension by the force of both springs.

If next the nuts 63 are tightened again, the first effect will be that disc 10 comes free so that its eccentricity may be altered. Further tightening of these nuts will also free disc 8 for radial movement.

In Fig. I the motion of the square was constrained by the use of four links, positioned so as to form two parallelograms, one between the base plate and a knee piece and another between the latter and the square. In Fig. IX the same principle is used in a somewhat different manner by combining the functions of pins 29 and 32 of Fig. I into a single pin and those of pins 30 and 33 into another single pin. As a result the knee piece 31 of Fig. IX has become a straight link of a length equal to the distance between the pins 5 and 6 which in turn was made equal to the distance between the pins 36 and 37, attached to the square 21.

One other modification to be noted in Fig. X is the construction of the scribe to be used when scribing on vertical surfaces, where the weight 45 of Fig. III becomes ineffective. The pencil guide 39 of Fig. X at its lower end is drilled to freely pass the lead 44. Its upper

end is bored out to provide a sliding fit for the sleeve 71, which is slipped over the lead 44. This sleeve also can slide in the bore of the nut 72, which may be screwed onto the thread 73, cut on the pencil guide 39 and be used to regulate the force of the spring 74 trapped between the nut and the sleeve 71. The pencil guide may again be slipped into the bushing 38 pressed into the square 21 and locked thereto by means of the screw 43. Thus the reaction of the light spring 74 is transferred to the square and via the flange 58 to the disc 8 and the spindle 7. The latter is mounted on the pivot pin 4, which has a washer 40 and gripping 41 on both sides. A light axial pressure on the knob 13, exercised while rotating it, will suffice to take up this reaction.

15 This ellipsograph is operated in a similar manner as those described before, except for the adjustment of the eccentricities of its discs, which is as follows:

First the knob is turned until the pointer 75, pressed in the square, is on the centerline of the scale 17a on the 20 base plate. In this position the slots 14 in the discs will be vertical and also the scribe will be on the Y-axis of the ellipse. In this position the knob is pushed down with a force sufficient to overcome the load of both springs inside the knob and the nuts 63 are tightened. After 25 releasing the pressure on the knob both discs will be free. The square is now moved so that the pointer travels along the scale 17a until the desired vertical eccentricity is indicated at the pointer. In this position again the knob is pushed down. This clamps the discs and permits 30 loosening the nuts 63 completely. When releasing the pressure the discs remain clamped.

Now the knob is turned until the pointer is on the centerline 17 of the horizontal scale on the base plate. The slots 14 will now be horizontal and the scribe is 35 on the X-axis of the ellipse. The knob is now depressed with a lesser force, sufficient to compress spring 65 only. After the nuts are tightened and the pressure released only disc 10 will be free and the pointer is moved along 40 scale 17 until the desired horizontal eccentricity is read on the scale. One more application of pressure on the knob and release of the nuts 63 completes the setting.

Having described three constructions incorporating the invention it will now be demonstrated that these devices produce ellipses that are mathematically correct.

45 For this purpose reference is made to Fig. VIII in which OX and OY are perpendicular axes through the origin O and OA and OB are vectors passing through O and making an angle of a^0 with the Y-axis. Let $OA=R$ be equal to the eccentricity of disc 10 and $OB=r$ to that of disc 8. Then when changing the angle a , the vector and points will describe concentric circular paths corresponding to the paths of the centers of the circular discs, when these are rotated. Thus the center O corresponds to the center of pin 4 and the angle of a^0 to the angle 50 of rotation of the disc assembly, measured from the position shown in Figs. I and V. In this position $a^0=0$, $x=0$ and $y=OB=r$. After rotating the disc assembly a^0 it will be noted from Fig. VIII that

$$x=OD=R \sin a \quad (1)$$

$$y=OE=r \cos a \quad (2)$$

but x is equal to the horizontal travel of the square measured from the point where $x=0$. It therefore corresponds to the distance of the scribe point to the vertical or y-axis of the ellipse. Further $(r-y)$ is equal to the vertical travel of the square, downward from the point where $y=r$. Therefore y is equal to the distance of the scribe point to the horizontal axis of the ellipse. Thus x and y are the coordinates of the scribe referred 55 to the axes of the ellipse to be drawn. But the Equations 60 to 70 1 and 2 may be transposed as follows:

$$\frac{x^2}{R^2} = \sin^2 a \quad (3)$$

$$\frac{y^2}{r^2} = \cos^2 a \quad (4)$$

which upon addition produce:

$$\frac{x^2}{R^2} + \frac{y^2}{r^2} = \sin^2 a + \cos^2 a = 1 \quad (5)$$

corresponding to the well known equation of an ellipse, with half axes R and r , referred to its principal axes.

In one of the Equation 3 or 4 the value of a may be changed to $a^0 + 180^\circ$, leaving the other equal to a^0 . This has no influence on Equation 5, which means that the same ellipse will be produced whether discs 8 and 10 are adjusted on the spindle 7, with the two eccentricities in the same or in the opposite direction.

We are aware that the following U. S. patents: 2,468,320, dated April 26, 1949; 2,595,417, dated May 6, 1952; 2,762,126 dated September 11, 1956; make use of the same mathematical theory outlined above and that all use two stacked discs that are rotated. All, however, have the scribe mounted on the discs, so that consequently each point of each disc must describe the ellipse with reference to stationary guides. This means that the operator must perform a complicated movement against a variable resistance. He furthermore simultaneously, with the same hand, must adjust the scribe pressure and in the first mentioned patent he must, moreover, with the other hand control the guide means. In all cases there are also frictional forces induced, that make the operation more difficult and the outcome more uncertain. In our invention all these difficulties are avoided. The friction has been reduced to a minimum and the operator must only turn a knob about its fixed center against a constant resistance. Therefore we believe to have contributed to the development of a simple, more easily manipulated ellipsograph. Furthermore if $R=r$, Equation 5 becomes that of a circle and if $R=r=0$ the scribe will not move. Therefore our ellipsograph is capable of tracing any imaginable ellipse between a point and the maximum size circle for which the instrument is designed and that can be drawn with this point as center.

We claim:

1. An ellipsograph comprising a spindle mounted for rotation about its axis, a pair of discs stacked eccentrically on said spindle in planes perpendicular to said axis, a structure having two flat surfaces perpendicular to each other and to said planes, means for maintaining contact between one of said surfaces and the periphery of one of said discs and of the other surface with the periphery of the other disc, means for constraining the motion of said structure to translation parallel to said planes, a scribe mounted on said structure and means for rotating said spindle.

2. An ellipsograph comprising a spindle mounted for rotation about its axis, a pair of circular discs stacked on said spindle in planes perpendicular to said axis, a radial slot in said discs for adjustably mounting said discs eccentrically on the spindle, a structure having two flat surfaces perpendicular to each other and to said planes, means for maintaining contact between one of said surfaces and the periphery of one of said discs and of the other surface with the periphery of the other disc, means for constraining the motion of said structure to translation parallel to said planes, a scribe mounted on said structure and means for rotating said spindle.

3. An ellipsograph comprising a base plate, a spindle mounted thereon for rotation about its axis, a pair of circular discs stacked on said spindle in planes perpendicular to said axis, a radial slot in said discs for adjustably mounting said discs eccentrically on the spindle, a structure having two flat surfaces perpendicular to each other and to said planes, means for maintaining contact between one of said surfaces and the periphery of one of said discs and of the other surface with the periphery of the other disc, means for constraining the motion of said structure to translation parallel to said

planes, a scribe mounted on said structure and means for rotating said spindle.

4. An ellipsograph comprising a base plate, a spindle mounted thereon for rotation about its axis, a pair of circular discs stacked on said spindle in planes perpendicular to said axis, a radial slot in said discs for adjustably mounting said discs eccentrically on the spindle, a structure having a substantially square internal opening, the opposite sides of said openings being in the same plane, adjacent sides being in different planes, each pair of parallel sides being in contact with one of said discs, means for constraining the motion of said structure to translation parallel to said planes, a scribe mounted on said structure and means for rotating said spindle.

5. An ellipsograph comprising a base plate, a spindle mounted thereon for rotation about its axis, a pair of circular discs stacked on said spindle in planes perpendicular to said axis, a radial slot in said discs for adjustably mounting said discs eccentrically on the spindle, a structure having a substantially square internal opening, the opposite sides of said opening being in the same plane, adjacent sides being in different planes, each pair of parallel sides being in contact with one of said discs, a floating knee piece, connected to said base plate by means of a pair of identical and parallel links and to said structure by means of another pair of identical and parallel links, a scribe mounted on said structure, a knob for clamping said discs to the spindle and revolving said spindle about said pivot pin.

6. An ellipsograph comprising a base plate, a pivot pin fixed to said base plate, a spindle mounted on said pivot pin so as to permit rotation of said spindle about its axis, a pair of circular discs stacked on said spindle in planes perpendicular to said axis, a radial slot in said discs for adjustably mounting said discs eccentrically on the spindle, a structure having a substantially square internal opening, the opposite sides of said opening being in the same plane, adjacent sides being in different planes, each pair of parallel sides being in contact with one of said discs, a floating knee piece, connected to said base plate by means of a pair of identical and parallel links and to said structure by means of another pair of identical and parallel links, a scribe mounted on said structure, a knob for clamping said discs to the spindle and revolving said spindle about said pivot pin.

7. An ellipsograph comprising a base plate, a pivot pin fixed to said base plate, a spindle mounted on said pivot pin so as to permit rotation of said spindle about its axis, a pair of circular discs stacked on said spindle in planes perpendicular to said axis, a radial slot in each disc permitting eccentric positioning of said discs on said spindle, means for aligning the center of said discs in a plane through the axis of said spindle, a structure having a substantially square internal opening, the opposite sides of said opening being in the same plane, adjacent sides being in different planes, each pair of parallel sides being in contact with one of said discs, a floating knee piece, connected to said base plate by means of a pair of identical and parallel links and to said structure by means of another pair of identical and parallel links, a scribe mounted on said structure, a knob for clamping said discs to the spindle and revolving said spindle about said pivot pin.

8. An ellipsograph comprising a base plate, a pivot pin fixed to said base plate, a spindle mounted on said pivot pin so as to permit rotation of said spindle about its axis, a pair of circular discs stacked on said spindle in planes perpendicular to said axis, a radial slot in each disc permitting eccentric positioning of said discs on said spindle, means for aligning the centers of said discs in a plane through the axis of said spindle, a structure having a substantially square internal opening, the opposite sides of said opening being in the same plane, adjacent sides being in different planes, each pair of parallel sides being in

contact with one of said discs, a floating knee piece, connected to said base plate by means of a pair of identical and parallel links and to said structure by means of another pair of identical and parallel links, a scribe mounted on said structure, a knob having internal resilient means for selectively clamping said discs to the spindle and revolving said spindle about said pivot pin.

9. An ellipsograph attachment for drafting machines comprising a base plate positioned on the drawingboard upon which the drafting machine operates, a pivot pin fixed to said base plate, the axis of said pivot pin being perpendicular to the drawingboard, a spindle rotatably mounted on said pivot pin, a pair of circular discs stacked on said spindle in planes perpendicular to said axis, a radial slot in said discs for adjustably mounting said discs eccentrically on the spindle, a structure having two flat surfaces perpendicular to each other and to said planes, means for maintaining contact between one of said surfaces and the periphery of one of said discs and of the other surface with the periphery of the other disc, means for fastening said structure to the scale bracket of the drafting machine, a scribe mounted on said structure and means for rotating said spindle.

10. An ellipsograph attachment for drafting machines comprising a base plate positioned on the drawingboard upon which the drafting machine operates, a pivot pin fixed to said base plate, the axis of said pivot pin being perpendicular to the drawingboard, a spindle rotatably mounted on said pivot pin, a pair of circular discs stacked on said spindle in planes perpendicular to said axis, a ra-

30 dial slot in said discs for adjustably mounting said discs eccentrically on the spindle, a structure having a substantially square internal opening, the opposite sides of said opening being in the same plane, adjacent sides being in different planes, each pair of parallel sides being in contact with one of said discs, means for fastening said structure to the scale bracket of the drafting machine, a scribe mounted on said structure, a knob for clamping said discs to the spindle and revolving said spindle about said pivot

10 pin.

11. An ellipsograph attachment for drafting machines comprising a base plate positioned on the drawingboard upon which the drafting machine operates, a pivot pin fixed to said base plate, the axis of said pivot pin being perpendicular to the drawingboard, a spindle rotatably mounted on said pivot pin, a pair of circular discs stacked on said spindle in planes perpendicular to said axis, a radial slot in said discs for adjustably mounting said discs eccentrically on the spindle, a structure having a substantially square internal opening, the opposite sides of said opening being in the same plane, adjacent sides being in different planes, each pair of parallel sides being in contact with one of said discs, means for fastening said structure to the scale bracket of the drafting machine, a scribe mounted on said structure, a knob having internal resilient means for selectively clamping said discs to the spindle and revolving said spindle about said pivot pin.
